(57) **CLAIM**

The ornamental design for a paint can receiving wrist sleeve with additional attachment points, as shown and described.

DESCRIPTION

FIG. 1 is a perspective view of a wrist sleeve showing my new design;

FIG. 2 is a top view of the wrist sleeve;

FIG. 3 is a bottom view of the wrist sleeve;

FIG. 4 is a front view of the wrist sleeve;

FIG. 5 is a rear view of the wrist sleeve;

FIG. 6 is a right side view of the wrist sleeve;

FIG. 7 is a left side view of the wrist sleeve;

FIG. 8 is a perspective view of the wrist sleeve attached to apex of a downwardly positioned bale handle of a paint can;

FIG. 9 is a perspective view of the wrist sleeve attached to the pivotal attachment point of a downwardly positioned

bale handle of a paint can; and,

FIG. 10 is a perspective view of the wrist sleeve attached to the apex of an upwardly positioned bale handle of a paint can.

The broken lines depict environmental structure and are for illustrative purposes only and form no part of the claimed design.
